UNITED STATES PATENT OFFICE.

MELVIN F. MURPHY, OF CHESTERFIELD, ILLINOIS.

PISTON-ALIGNING TOOL.

Application filed March 25, 1922. Serial No. 546,912.

To all whom it may concern:

Be it known that I, MELVIN F. MURPHY, a citizen of the United States, residing at Chesterfield, in the county of Macoupin and State of Illinois, have invented certain new and useful Improvements in Piston-Aligning Tools, of which the following is a specification.

This invention relates to tools and the primary object of the invention is to provide a simple, light and inexpensive tool for aligning pistons with their respective cylinders, irrespective of whether the pistons are out of alignment due to a bent crank shaft, bent connecting rod, or worn connecting rod bearings.

Another object of the invention is the provision of a portable piston aligning tool, which is adapted to detachably engage directly with the cylinder of an engine, with which the piston is to be aligned, the tool effectively indicating whether or not the piston is in direct alignment with its cylinder.

A further object of the invention is the provision of a novel piston aligning tool, which can be readily and quickly connected with a piston, and which embodies novel means for connection with the cylinder, and a novel aligning bar carried by said means, the aligning bar being mounted for swinging movement so that the same can be moved past the piston being aligned.

A further object of the invention is the provision of novel means for connecting the aligning bar with the cylinder engaging means, so that the said aligning bar will always be held in proper aligned relation with the cylinder, and so that the aligning bar will be held against lateral shifting movement in relation to the cylinder connecting means.

A still further object of this invention is the provision of a novel piston aligning tool of durable construction, one which can be manufactured and placed upon the market at a small cost, and one which can be attached to a cylinder by an ordinary layman.

With these and other objects in view, the invention consists in the novel construction, arrangement and formation of parts, as will be hereinafter more specifically described, claimed and illustrated in the accompanying

drawings, forming a part of this specification, in which drawings:

Figure 1 is an elevation of the improved piston aligning tool, showing the same in operative relation to an engine, the engine being shown in longitudinal section.

Figure 2 is an edge elevation of an improved piston aligning tool, showing the same in operative relation to an engine, the engine being shown in transverse section.

Figure 3 is an enlarged front elevation of the improved piston aligning tool.

Figure 4 is an enlarged fragmentary vertical section through the improved tool, illustrating the means utilized for connecting the aligning bar with the cylinder engaging means, taken on the line 4-4 of Figure 7.

Figure 5 is a vertical transverse section through the improved tool, taken on the line 5-5 of Figure 7.

Figure 6 is a vertical transverse section through the improved tool, taken on the line 6-6 of Figure 7.

Figure 7 is a top plan view of the improved tool.

Figure 8 is an enlarged fragmentary edge elevation of the same.

Figure 9 is a detail horizontal section through the tool, taken on the line 9-9 of Figure 3, illustrating the means for detachably receiving the aligning bar to permit the aligning bar to be connected with the piston engaging means.

Figure 10 is a fragmentary detail perspective view of the head utilized for connecting the aligning bar to the piston.

Referring to the drawings in detail, wherein similar reference characters designate corresponding parts throughout the several views, the letter A generally indicates the improved tool; and B, an engine with which it can be used.

The engine B is, of course, of the ordinary or any preferred character, and forms no part of the present invention, but simply has been shown for the purpose of illustrating the use of the improved tool.

As shown, the engine B includes cylinders 5, cast in blocks of two, and each of the cylinders forming a block being divided by common piston wall 6. The cylinder blocks are mounted in the usual manner upon the

crank case 7, which supports depending bearings 8 for the reception of the crank shaft 9. The crank shaft 9 has detachably connected thereto by means of bearings 10 the connecting rods 11 and the pistons 12, which are reciprocably mounted in the cylinders 5 in the ordinary manner. It is of course, apparent that when the tool A is to be used, to see if the pistons are in correct alignment with their cylinders, that the lower part or oil pan of the crank case 7 is removed, and the connecting rod of the piston which is to be aligned removed from its crank shaft, so that the piston 12 can be pulled out from the cylinder, after which the connecting rod is again connected to the crank shaft and the piston permitted to hang from the crank shaft as clearly shown in Figures 1 and 2 of the drawings.

20 The tool A includes means C for engaging a cylinder for holding the tool A in position, the aligning bar D and the means E for connecting the aligning bar D with the connecting means C.

25 The means C for holding the tool in position comprises a cylindrical solid body 15 having its intermediate portion cut out or notched, as at 16. One wall of the notched portion 16 is curved, arcuately, as at 17', to conform to the interior configuration of a cylinder. One end of the body 15 is provided with an outwardly extending screw threaded stem 17, on which is threaded a head 18. The head 18 is roughened or serrated on its outer face, so that the same can be conveniently grasped by the hand, and one end of the head 18 is pointed as at 19, so that the same will frictionally engage the bore of a cylinder. It is obvious that by adjusting the head 18, the same will be moved toward or away from the bore of a cylinder diametrically opposite the point engaged by the arcuate face 17'. The opposite end of the body 15 from the screw threaded stem 40 17 is provided with an inwardly extending bore 20, in which is threaded a screw 21. This screw can also be provided with a pointed inner terminal 22 for biting engagement with the wall of a cylinder. The outer end of the screw 21 can be provided with a head 24, which can be readily engaged by the hand of the operator to permit the free turning movement thereof.

55 The aligning bar D is formed from a flat strip of metal, and includes the longitudinally extending relatively narrow rectangular body 25. This bar is connected with the cylindrical body 15 for swinging movement by the means E which will now be described. 60 It is obvious that the aligning bar D can be connected with the body 15 in various ways, and one of these ways has been shown by way of example in the drawings. As shown, the connecting means E includes a barrel 26 for rotatably receiving the body

16, and depending ears 27 and 28 for receiving the upper end of the rod D. The barrel 26 and the ears 27 and 28 can be made out of one piece, if so desired, and in the drawings, this has been shown in this manner. In order to form the barrel 26 and the ears 27 and 28 a strip of metal is taken and rolled intermediate its ends to provide the barrel and the ears 27 and 28 are bent downwardly in spaced relation as clearly shown in Figures 5, 6, and 10 of the drawings. In order to hold the ears 27 and 28 in spaced relation to receive the aligning rod D, the spacing blocks 29 can be provided. The spacing blocks 29 are also arranged in spaced relation, and these blocks with the ears 27 and 28 define a way 30, which is adapted to snugly receive the upper end of the aligning rod D. This aligning rod D is held by a screw 31, which is adapted to extend through the ears 27 and 28 and through the rod D.

In order to prevent lateral shifting movement of the barrel 26 upon the body 15, the body may have threaded into the same at each end thereof screws 35, the heads of which are adapted to overlie the terminals of the barrel 26. This is clearly shown in Figures 3, 4, and 8 of the drawings.

In use of the improved tool, the piston to be aligned with the cylinder is swung down out of its cylinder as heretofore described, and shown in Figures 1 and 2 of the drawings. The screw 21 is then actuated, so as to move the same outward and away from the curved wall 17. The tool is then placed in the engine so that the dividing wall 6 between a pair of cylinders can extend into the notched or cut out portion 16, after which the screw 21 is again turned to feed the pointed end 22 into tight contact with the cylinder. After the screw 21 has been adjusted, the head 18 is rotated, so as to move the pointed end 19 into engagement with an opposite wall of the cylinder from the wall engaged by the curved face 17'. This means effectively holds the body 15 against movement and the inner edge of the aligning rod D will be in direct alignment with the face 17' and the wall of the cylinder with which the piston is to be aligned. The rod D can now be swung back and forth across the outer face of the piston which is to be aligned, and any variation in the contour of the piston will be at once noted irrespective of whether the piston is out of alignment due to a worn bearing, or due to a bent connecting rod or crank shaft. If the tool shows that the piston is out of alignment, the next step would then be taken to bring the same into direct alignment with the cylinder, by any suitable means.

From the foregoing description, it can be seen that a novel and simple portable tool

has been provided, which will effectively and simply permit a person to determine whether or not a piston is in alignment with its cylinder.

5 Changes in details may be made without departing from the spirit or scope of this invention; but,

I claim:

1. A piston aligning tool comprising an 10 abutment having a contour conforming to the inner wall of the cylinder, means for detachably holding said abutment into engagement with the said inner wall, and an aligning rod carried by said means having one of its longitudinal edges disposed in alignment with the face of the abutment.

2. In a tool for aligning pistons with a cylinder of an internal combustion engine, said tool comprising a clamping member including a body having a notched portion arranged to receive one wall of the cylinder of the engine, and means for clamping the body in position in the cylinder with one face of the notch engaging the inner wall 25 of the cylinder, and a depending rockable aligning rod carried by the body for engaging the outer circumference of the piston longitudinally thereof when withdrawn from the cylinder.

30 3. A tool for aligning the piston with the cylinder of an internal combustion engine, said tool comprising a clamping member adapted for detachable engagement with the wall of the cylinder, an aligning rod 35 carried by the clamping member and normally held in direct alignment with the wall of the cylinder of the engine with which the clamp is associated, the rod being adapted to engage the outer circumference 40 of the piston longitudinally thereof when withdrawn from the cylinder.

4. A tool for aligning a piston with the cylinders of an internal combustion engine, said tool comprising a head having a notch 45 formed therein, for receiving the wall of the cylinder, one wall of the notch portion being curved to conform to the configuration of the cylinder with which the piston is to be aligned, a set screw carried by the body for 50 engaging the cylinder for bringing the arcuate face into intimate engagement with the inner face of the cylinder, a threaded shank carried by the body, a head threaded upon the stem adjacent the wall of the cylinder at a point diametrically opposite the 55 point engaged by the opposite face of the notch portion of the body, a connecting member rockably mounted upon the body, and an aligning rod detachably secured to

the connecting member to engage the outer 60 circumference of the piston longitudinally thereof when withdrawn from the cylinder.

5. As a new article of manufacture, a tool comprising a body having a recess portion to receive the connecting walls intermediate 65 a pair of cylinders, means carried by the body for engaging the inner wall of one of the cylinders at opposite points, and a piston aligning member loosely connected to the body and disposed at right angles thereto 70 for engaging the outer circumference of the piston longitudinally thereof when withdrawn from the cylinder.

6. As a new article of manufacture, a tool comprising a body having a recessed portion 75 to receive the connecting wall intermediate a pair of cylinders, one wall of the recess having a curved face to conform to the contour of the inner wall of one of the cylinders, means for engaging said curved face 80 with the wall of the cylinder, and a piston engaging bar having one of its edges disposed in alignment with the curved face for engaging the outer circumference of the cylinder longitudinally thereof when withdrawn from the cylinder.

7. As a new article of manufacture, a portable piston aligning tool comprising a body having a recess portion therein arranged to receive the connecting wall intermediate the pair of cylinders, a thumb screw carried by one end of the body for extending into the notch portion, and outwardly extending screw threaded shanks carried by the other end of the body, a head fitted upon 95 the shank, and a piston engaging bar loosely connected with the body and having one of its longitudinal edges normally disposed in alignment with one of the walls of the recess portion for engaging the outer circumference of the cylinder longitudinally thereof when withdrawn from the cylinder.

8. As a new article of manufacture, a portable piston aligning tool comprising a solid body having a notched portion therein arranged to receive the connecting wall intermediate a pair of cylinders, a thumb screw carried by one of the bodies for extending into the notch portion, an outwardly extending screw threaded stem carried by the other end of the body, a head fitted upon the stem, a connecting member including a barrel rockably mounted upon the body, depending ears formed on the barrel, and relatively thin piston engaging bar detachably 110 connected with said depending ears.

MELVIN F. MURPHY.
